UNITED STATES PATENT OFFICE

DANIEL BAJUSZ, OF VINTONDALE, PENNSYLVANIA.

TOY.

1,330,511.

Specification of Letters Patent.

Patented Feb. 10, 1920.

Application filed October 14, 1919. Serial No. 330,561.

To all whom it may concern:

Be it known that I, DANIEL BAJUSZ, a citizen of Hungary, residing at Vintondale, in the county of Cambria and State of Pennsylvania, have invented certain new and useful Improvements in Toys, of which the following is a specification.

The primary object of the invention is to provide a toy adapted for shooting missiles with great force and accuracy, the invention being simple in construction, easy and inexpensive to manufacture.

A further object of the invention is to provide a toy shooter readily secured to a support when desired and capable of shooting one or a plurality of missiles, adjusting means being provided for changing the capacity of the shooter.

With these general objects in view, the invention consists in the combination and arrangement of parts hereinafter fully described, in connection with the accompanying drawings, and in which like reference characters designate corresponding parts throughout the several views.

In the drawings,

Figure 1 is an elevational view of the invention set or extended,

Fig. 2 is a longitudinal sectional view thereof in its normal position showing a marble ready for shooting,

Fig. 3 is a sectional view taken upon line III—III of Fig. 2,

Fig. 4 is an end elevation of the toy looking in the direction of the muzzle,

Fig. 5 is a perspective view taken upon line V—V of Fig. 3, and

Fig. 6 is an elevational view of the opposite or firing end of the main frame portion of the toy.

Referring more in detail to the drawings, a skeleton frame or casing 10 is provided having opposite rectangular ends 11 and 12 and sides 13, one of which may be provided with openings 14 therein if desired.

A longitudinal partition 15 substantially centrally of the casing 10 has a longitudinal slot 16 terminating in circular openings 17 and 18 centrally of the ends 11 and 12. A barrel 19 longitudinally slidable in the slots 16 through the openings 17 and 18 has laterally projecting pins 20 slidably mounted in guide grooves 21 in the opposite edges of the slots 16. It will be seen that the barrel 19 may slide longitudinally of the casing 10

prevented from rotation by the pins 20 in the grooves 21.

A coil spring 22 surrounds the barrel 19 with its opposite ends connected to the casing end 12 as at 23 and to an annular shoulder 24 of the barrel as at 25. A shaft 26 is longitudinally adjustably positioned within the barrel 19 having a slightly enlarged portion 27 of the shaft threaded into a screw threaded portion 28 of the barrel 19. A reduced extension or rod 29 of the shaft slides through a perforation 30 in the outer end of the barrel 19 and is provided with a cross handle 31 whereby the shaft is turned for adjustment within said barrel. A spring 32 between a head 33 at the outer end of the shaft rod 29 and the outer end 34 of the barrel 19 prevents the rod from accidental turning in the barrel although permitting the adjustment of the shaft when desired.

An annular depression 35 in the outer face of the end 11 forms a muzzle 36 centrally of said end and with which the outer end of the barrel 19 is normally positioned flush by the spring 22. The sides of the bore through the barrel 19 are beveled as at 37 adjacent the muzzle end of the toy and a missile such as the marble 38 is readily positioned therein seated upon the adjacent end of the shaft 26. By retracting the shaft 26 to a greater extent, more missiles may be seated in the muzzle end of the barrel for shooting and it will be understood that missiles of different size may be employed with the toy.

The complete operation of the invention will be apparent from this detailed description thereof, the relative position of the parts being normally as shown in Figs. 2 and 3 of the drawings. The marble 38 being placed in position, the handle 31 is grasped and the barrel forced outwardly against the action of the spring 29 while the casing 10 is firmly held by the operator. Upon releasing the handle 31, the spring 32 draws the barrel 19 forcibly through the slot 16 and projects the missile 38 with great force through the muzzle 36 of the toy. Cords 39 limit the outward movement of the barrel being connected between the collar 24 and the casing end 12. A protecting disk 40 is also mounted adjacent the outer end of the barrel 19. The toy may be readily held in the hand when being employed although a flange extension 41 of one of the sides 13 of the casing may be secured to a permanent

support and openings 42 are provided in the flange for suitable holdfast devices, not shown. While the form of the invention set forth is believed preferable, it will be understood that minor changes may be made therein without departing from the spirit and scope of the invention as hereinafter claimed.

What I claim as new is—

10 1. A shooter comprising a casing having a passage therethrough, a barrel slidable through said passage, a spring normally holding the barrel within the passage adapted for extension upon setting the shooter for operation and adjustable means within the barrel adapted for changing the capacity of the shooter at will.

20 2. A shooter comprising a casing having opposite ends with central perforations, a partition through the casing having a slot terminating in said perforations, a barrel slidable through said slot and perforations, means adapted to prevent rotation of the barrel, a spring adapted to return the barrel to its normal position when forcibly retracted, and means within the barrel for engaging a missile in firing position and having an extension outwardly of the barrel adapted for grasping in projecting the latter.

30 3. A shooter comprising a casing having opposite ends with central perforations, a partition through the casing having a slot terminating in said perforations, a barrel slidable through said slot and perforations, means adapted to prevent rotation of the barrel, a spring adapted to return the barrel to its normal position when forcibly retracted, a shaft threaded in the barrel with one end inwardly of the muzzle end of the barrel adapted for accommodating missiles, an extension rod carried by the shaft projecting through the other end of the barrel and an operating handle upon the outer end of said rod.

40 4. A shooter comprising a casing having opposite ends with central perforations, a partition through the casing having a slot terminating in said perforations, a barrel slidable through said slot and perforations, means adapted to prevent rotation of the barrel, a spring adapted to return the barrel to its normal position when forcibly retracted, a shaft threaded in the barrel with one end inwardly of the muzzle end of the barrel adapted for accommodating missiles, an extension rod carried by the shaft projecting through the other end of the barrel, an operating handle upon the outer end of said rod, a spring between the outer end of the rod and barrel adapted for preventing accidental turning of the shaft, cords connected between the barrel and adjacent end of the casing adapted for limiting the projection of the barrel during the extending of

the spring and a mounting flange carried by the casing.

5. A toy comprising a casing, a flange upon the casing adapted for mounting the toy upon a support, one side of the casing having openings therein, a transverse partition within the casing having a longitudinal slot provided with opposite grooves, perforations in the ends of the casing in alignment with said slot, one end of the casing having an annular cut away portion forming a muzzle surrounding the perforation thereof, a barrel slidable through said slot and perforations having a bore with its outer end beveled normally positioned adjacent said muzzle adapted for the reception of missiles, projecting pins carried by the barrel slidable in said grooves, an annular shoulder upon the barrel exteriorly of the opposite end of the casing from said muzzle, a normally retracted spring surrounding the barrel with its ends secured to said shoulder and the adjacent end of the casing and means for limiting the introduction of missiles in the muzzle end of the barrel and for retracting the barrel outwardly of the casing during the extending of said spring.

6. A toy comprising a casing, a flange upon the casing adapted for mounting the toy upon a support, one side of the casing having openings therein, a transverse partition within the casing having a longitudinal slot provided with opposite grooves, perforations in the ends of the casing in alignment with said slot, one end of the casing having an annular cut away portion forming a muzzle surrounding the perforation thereof, a barrel slidable through said slot and perforations having a bore with its outer end beveled normally positioned adjacent said muzzle adapted for the reception of missiles, projecting pins carried by the barrel slidable in said grooves, an annular shoulder upon the barrel exteriorly of the opposite end of the casing from said muzzle, a normally retracted spring surrounding the barrel with its ends secured to said shoulder and the adjacent end of the casing, a shaft within the barrel having a portion thereof in threaded engagement with the interior of the barrel and the outer end of the shaft spaced inwardly of the outer end of the barrel, a rod extension upon the shaft projecting outwardly of the barrel, a handle carried by said extension, means surrounding said extension adapted for preventing the accidental turning of said rod and shaft.

7. A toy comprising a casing, a flange upon the casing adapted for mounting the toy upon a support, one side of the casing having openings therein, a transverse partition within the casing having a longitudinal slot provided with opposite grooves, perforations in the ends of the casing in alignment with said slot, one end of the casing

having an annular cut away portion forming a muzzle surrounding the perforation thereof, a barrel slideable through said slot and perforations having a bore with its 5 outer end beveled normally positioned adjacent said muzzle adapted for the reception of missiles, projecting pins carried by the barrel slideable in said grooves, an annular shoulder upon the barrel exteriorly of the 10 opposite end of the casing from said muzzle, a normally retracted spring surrounding the barrel with its ends secured to said shoulder and the adjacent end of the casing, a shaft within the barrel having a portion thereof in 15 threaded engagement with the interior of

the barrel and the outer end of the shaft spaced inwardly of the outer end of the barrel, a rod extension upon the shaft projecting outwardly of the barrel, a handle carried by said extension, means surrounding 20 said extension adapted for preventing the accidental turning of said rod and shaft, a protecting disk upon the outer end of the barrel outwardly of said shoulder, and movement limiting cords secured between 25 said shoulder and the adjacent end of the casing.

In testimony whereof I affix my signature.

DANIEL BAJUSZ.
